CLAIM

The ornamental design for a package, as shown and described.

DESCRIPTION

FIG. 1 is a top plan view of a package showing a first embodiment of the new design;
 FIG. 2 is a bottom plan view of the package shown in FIG. 1;
 FIG. 3 is a front elevation view of the package shown in FIG. 1;
 FIG. 4 is a rear elevation view of the package shown in FIG. 1;
 FIG. 5 is a right side view of the package shown in FIG. 1;
 FIG. 6 is a left side view of the package shown in FIG. 1;
 FIG. 7 is a top perspective view of the package shown in FIG. 1;
 FIG. 8 is a top perspective view of the package shown in FIG. 1;
 FIG. 9 is a top perspective view of the package shown in FIG. 1;
 FIG. 10 is a bottom perspective view of the package shown in FIG. 1;
 FIG. 11 is a bottom perspective view of the package shown in FIG. 1;
 FIG. 12 is a bottom perspective view of the package shown in FIG. 1;
 FIG. 13 is a top plan view of the package shown in FIG. 1 illustrating the package in an unfolded orientation;
 FIG. 14 is a top plan view of a package showing a second embodiment of the new design;
 FIG. 15 is a bottom plan view of the package shown in FIG. 14;
 FIG. 16 is a front elevation view of the package shown in FIG. 14;
 FIG. 17 is a rear elevation view of the package shown in FIG. 14;
 FIG. 18 is a right side view of the package shown in FIG. 14;
 FIG. 19 is a left side view of the package shown in FIG. 14;
 FIG. 20 is a top perspective view of the package shown in FIG. 14;

FIG. 21 is a top perspective view of the package shown in FIG. 14;
 FIG. 22 is a top perspective view of the package shown in FIG. 14;
 FIG. 23 is a bottom perspective view of the package shown in FIG. 14;
 FIG. 24 is a bottom perspective view of the package shown in FIG. 14;
 FIG. 25 is a bottom perspective view of the package shown in FIG. 14;
 FIG. 26 is a top plan view of the package shown in FIG. 14 illustrating the package in an unfolded orientation;
 FIG. 27 is a top plan view of a package showing a third embodiment of the new design;
 FIG. 28 is a bottom plan view of the package shown in FIG. 27;
 FIG. 29 is a front elevation view of the package shown in FIG. 27;
 FIG. 30 is a rear elevation view of the package shown in FIG. 27;
 FIG. 31 is a right side view of the package shown in FIG. 27;
 FIG. 32 is a left side view of the package shown in FIG. 27;
 FIG. 33 is a top perspective view of the package shown in FIG. 27;
 FIG. 34 is a top perspective view of the package shown in FIG. 27;
 FIG. 35 is a top perspective view of the package shown in FIG. 27;
 FIG. 36 is a bottom perspective view of the package shown in FIG. 27;
 FIG. 37 is a bottom perspective view of the package shown in FIG. 27;
 FIG. 38 is a bottom perspective view of the package shown in FIG. 27;
 FIG. 39 is a top plan view of the package shown in FIG. 27 illustrating the package in an unfolded orientation;
 FIG. 40 is a top plan view of a package showing a fourth embodiment of the new design;
 FIG. 41 is a bottom plan view of the package shown in FIG. 40;
 FIG. 42 is a front elevation view of the package shown in FIG. 40;
 FIG. 43 is a rear elevation view of the package shown in FIG. 40;
 FIG. 44 is a right side view of the package shown in FIG. 40;
 FIG. 45 is a left side view of the package shown in FIG. 40;
 FIG. 46 is a top perspective view of the package shown in FIG. 40;
 FIG. 47 is a top perspective view of the package shown in FIG. 40;
 FIG. 48 is a top perspective view of the package shown in FIG. 40;
 FIG. 49 is a bottom perspective view of the package shown in FIG. 40;
 FIG. 50 is a bottom perspective view of the package shown in FIG. 40;
 FIG. 51 is a bottom perspective view of the package shown in FIG. 40; and,
 FIG. 52 is a top plan view of the package shown in FIG. 40 illustrating the package in an unfolded orientation.
